UNITED STATES PATENT OFFICE

WILLIAM J. MOLONEY, OF SEATTLE, WASHINGTON

LOG CARRYING BARGE

Application filed November 5, 1931. Serial No. 573,189.

This invention relates to vessels or barges especially adapted for the shipment of large timbers, logs, lumber or any other similar materials and has for the primary object, 5 the provision of a device of the above stated character, whereby floating materials of the stated character may be easily and quickly loaded into the vessel or barge without undue handling or the employment of hoists or similar apparatus.

Another object of this invention is the provision of a hull constructed in such a way as to provide a comparatively large cargo space having one end arranged to receive and discharge the cargo therefrom.

A further object of this invention is the provision of means for sinking or submerging the hull in the water at desired depths to permit floating logs or the like to be 20 guided therein and stacked one upon the other until the cargo space is filled and the hull then raised or floated to its normal draft, whereby the barge may proceed to its destination.

A further object of this invention is the provision of means, whereby the hull may be submerged for the purpose of unloading the logs or the like into the body of water and during the unloading operation to be 30 gradually raised by increasing its buoyancy for permitting the uppermost layer of logs to be unloaded and the succeeding layers of logs to be unloaded as the preceding layer of logs are floated or moved away from the barge.

A still further object of this invention is the provision of a log carrying barge of the above stated character which will be 40 simple, durable and efficient and which may be manufactured and sold at a comparatively low cost.

With these and other objects in view, this invention consists in certain novel features 45 of construction, combination and arrange-

ment of parts to be hereinafter more fully described and claimed.

For a complete understanding of my invention, reference is to be had to the following description and accompanying drawings, in which:

Figure 1 is a top plan view illustrating a vessel or barge constructed in accordance with my invention.

Figure 2 is a side elevation illustrating the same.

Figure 3 is a sectional view taken on the line 3—3 of Figure 1.

Figure 4 is a sectional view taken on the line 4—4 of Figure 1.

Figure 5 is a rear elevation illustrating the stern of the vessel or barge.

Figure 6 is a transverse sectional view taken on the line 6—6 of Figure 1.

Figure 7 is a similar view illustrating the cargo space filled with layers of logs or the like and with the hull in a substantially full submerged position.

Referring in detail to the drawings, the numeral 1 indicates the hull of a barge or vessel having a flat bottom 2, straight sides 3, a bow 4 and a stern 5.

The bow 4 has the front walls 6 thereof inclining forwardly and upwardly from the bottom 2. A transverse partition 7 is arranged in the bow 4 and cooperates with the bottom 2 and sides 3 in forming a cargo carrying space 8 that opens outwardly through the stern 5 and normally closed by hinged gates or doors 9 provided with a suitable fastening means 10 for retaining them in a closed position. The fastening means 10 is adapted to be manually operated when desiring to open the gates or doors

9 for the purpose of loading or unloading the cargo space. It is to be understood that the gates or doors swing outwardly and when in a closed position, the force of the water thereagainst will aid in retaining

the gates or doors in a closed position. The gates are provided with drain valves 9'.

The bottom 2 has formed therein a plurality of compartments or tanks 11 formed by a plurality of partitions cooperating with the bottom 2 and the bottom supporting wall 12 of the cargo space 8. The sides 3 are of hollow formation and divided by a plurality of partitions 13 to provide side tanks or compartments, the walls of which are strengthened by diagonally extending braces 14. The compartments 11 or the walls thereof are strengthened by diagonally extending braces 15. The upper portions 10 of the sides, bow and stern are closed by a deck 16, leaving the cargo space 8 open at the upper end thereof.

By referring to Figures 4, 6 and 7 it will be noted that the compartments in the 20 sides 3 extend the full length of the latter and are arranged one above the other, providing means for submerging the hull to desired depths by filling first the bottom compartments 15 and then the side compartments in the side walls.

The various compartments are each provided with a sea cock 17 having an operating medium 18 extending through the deck 16. Vent pipes 19 extend through the decks and 30 communicate with the various compartments. Suction pipes 20 extend through the decks to the various compartments and are adapted for connection with a suitable pump located on the barge (and not shown). The suction pipes by being connected to the 35 pump are adapted to draw water from the various tanks when desiring to raise the barge from a submerged position as shown in Figure 7 to a position of ordinary draft.

40 The bow 4 may have a living compartment 21 arranged therein provided with a stairway 22 leading to a hatch 23 in the deck of the bow. The stern and bow may be each provided with a towing post 24.

45 The side walls of the cargo carrying space 8 are provided with rows of eyes or like fasteners 25 to which anchoring elements 26 may be secured for the purpose of tying down logs in layers and one upon the other 50 as shown in Figure 7 for the purpose of preventing shifting of the logs during transit. A ladder 27 may be arranged on the partition 7 at the closed end of the cargo carrying space 8 whereby a person may descend 55 or ascend from the cargo space with ease.

It is customary to receive logs, timbers or lumber from a saw mill by floating them down streams until they reach bodies of water that are navigable and to facilitate 60 the shipment of these logs or timbers to foreign points, my vessel or barge may be economically employed due to the ease in which the logs or timbers may be loaded therein or unloaded therefrom when desired 65 without the employment of hoist or similar

apparatuses. To load the barge, the stern is arranged towards the floating logs and the gates or doors 9 placed in an open position and the hull is then submerged to a sufficient depth to permit the logs to be 70 guided or floated into the cargo carrying space 8 and arranged in a layer as shown in Figure 6 and then tied down by anchoring elements 25. After the first layer has been tied down, the hull is again submerged to a 75 greater depth permitting other logs to be floated into the cargo space and arranged in a layer upon the preceding logs and then tied down by anchoring elements 26. This method of loading and submerging of the 80 hull is continued until the cargo carrying space is filled as shown in Figure 7. The gates at the ends of the vessel are then closed and the valves which are situated in these 85 gates are opened. The pump (not shown) is set in operation to extract the water from the various compartments permitting the buoyancy of the compartments to raise the hull of the vessel to its ordinary sea going draft. As the hull raises the water which is 90 in and around the logs will flow by gravity through the open valves in the gates. When all the water has been emptied from the various compartments and the vessel has reached her sea going draft, these valves in 95 the gates are then closed. After the cargo of logs have traveled to their destination and it is desired to unload them, the valves 9' are opened, permitting water to enter the barge about the logs and the hull is 100 submerged to a depth that permits the uppermost layer of logs to float outwardly of the space 8 after the opening of the gates and the untying of the uppermost anchoring elements 26. As the uppermost layer of 105 logs pass from the vessel, the pump is started in operation gradually raising the hull and the next layer of logs is released and allowed to float outwardly of the hull. This operation is continued until all of the layers of 110 logs have been removed.

While I have shown and described the preferred embodiment of my invention, it will be understood that minor changes in construction, combination and arrangement of 115 parts may be made without departing from the spirit and scope of my invention, as claimed.

Having described my invention, what I claim is:

A log carrier comprising a hull having one end opened and its opposite end permanently closed and provided with a log cargo chamber communicative with the opened end of said hull, a plurality of compartments arranged at the sides and under the cargo chamber within said hull, outwardly swinging gates for opening and closing the opened end of the hull to permit logs to be floated into and out of said chamber.

ber, and means to admit and exhaust water to said compartments for causing partial submerging of the hull in the water and floating thereof to its normal draft so that
5 logs may be floated into and out of the chamber without the use of hoisting means, and valves in said gates whereby water may be admitted to the cargo chamber for aiding in submerging the hull and to equalize the
10 water pressure on both sides of the gates and to drain water from the cargo chamber after the raising of said hull.

In testimony whereof I affix my signature.
WILLIAM J. MOLONEY.
